MACHINE FOR MAKING CARBOYS OR LARGE GLASS CONTAINERS.

1,334,647.

Specification of Letters Patent. Patented Mar. 23, 1920.

Application filed December 2, 1918. Serial No. 265,040.

To all whom it may concern:

Be it known that I, HARRY M. BROWN, a citizen of the United States, residing at Brooklyn, in the county of Kings and State 5 of New York, have invented a new and useful Improvement in Machines for Making Carboys or Large Glass Containers, of which the following is a specification.

This invention relates particularly to a 10 machine adapted to use in the manufacture of carboys, or other large glass containers; and the primary object is to provide a machine which is simple in construction, easy of operation, and of large output capacity, 15 adapted for the commercial production of carboys, or other large containers, provided with internally-threaded mouth-portions adapted to receive threaded stoppers.

A further object is to provide an exceedingly simple machine of the character indicated, which is labor-saving in operation.

The invention is illustrated, in a preferred simple embodiment, in the accompanying drawings, in which—

25 Figure 1 represents a broken vertical sectional view of the improved machine or press, the dotted lines indicating the bodily shifted position of the plunger and its actuating mechanism; Fig. 2, a horizontal sectional view taken approximately as indicated at line 2 of Fig. 1; Fig. 3, a broken rear elevational view; Fig. 4, a sectional view taken as indicated at line 4 of Fig. 1; Fig. 5, a vertical sectional view of the 30 valve device controlling the operation of the plunger for forcing the molten metal into the neck-mold, the section being taken as indicated at line 5 of Fig. 6; and Fig. 6, a horizontal sectional view taken as indicated 35 at line 6 of Fig. 5.

In the embodiment illustrated, A represents the bed, or base-plate, of the machine, mounted on legs A¹; B, a three-part neck-mold mounted on the bed A; C, an arbor 45 having one end projecting into the mold B and equipped with a thread adapted to form an interior thread in the bottle-mouth and having a shaft equipped with a thread of corresponding pitch which engages the 50 threaded bore of a fixed bearing; and D, mechanism for forcing molten metal into the mold B, said mechanism being mounted on a carriage D¹, which is shiftable on the

bed-plate A by means of mechanism D². The carriage D¹ has its uprights equipped 55 with elongated mold-locking cams D³ (one shown in full lines and one in dotted lines, in Fig. 2), which serve to lock the closed mold, both when the mechanism D is in the full-line and the dotted line position shown 60 in Fig. 1. When, however, the carriage D¹ is wholly retracted, the mold can be opened to permit removal of the carboy.

The frame of the machine may be of any suitable construction. Preferably it comprises the bed-plate A supported as shown; and the construction of the machine is such as to permit a carboy E to be disposed horizontally in front of the machine, with the neck of the carboy projecting into the 70 mold B.

The carboy is usually blown in an iron mold, in which it is formed with a neck-portion 1, which requires to be reinforced and provided with an internal thread, which operation is performed in the machine herein described. While the carboy, or the neck-portion thereof, is hot, it is entered in the mold B; and a ball of hot or molten glass is introduced and pressed into the mold, the 75 mandrel being in the position shown in Fig. 1. In this operation, the head and mouth-portion of the carboy is formed and becomes practically integral with the neck of the carboy, and the mouth-portion is provided 80 with an internal thread. The mandrel is then unscrewed and withdrawn and the carriage D¹ wholly retracted, which enables the mold to be opened, thus permitting the carboy to be lifted out of the mold. The carboy is then placed in an annealing furnace, 85 where it remains until properly tempered.

The mold B comprises a lower half-section 2, which is firmly secured upon the bed-plate A by any suitable means (not 95 shown), and a pair of upper quarter-sections 3 equipped with arms 3^a which are connected by horizontal pivots 4 with pivot-lugs 5, which project laterally from the lower mold-section 2. The upper mold-sections 3 are provided with upward extensions 3^b, which together form a tubular upper extension of the mold and afford a cavity 6 adapted to hold the charge of molten metal, or plastic glass, which is to be pressed into 100 the mold, to form the carboy-head. The 105

semi-cylindrical upward extensions 3^b have their outer sides equipped with lock-engaging lugs 3^c, adapted to be engaged by the mold-locking cams D^a.

5 The neck-mold B is adapted to be opened and closed by means of a vertical plunger 7, working through the bed-plate A and equipped at its upper end with a cross-head 7^a; a pair of links 7^b connecting said cross-head with the arms 3^a of the quarter-sections 3 of the mold; and a foot-lever 7^c whose inner end is connected by a link 7^d to the lower end of the plunger 7. Assuming the mold to be unlocked, depression of the outer 10 end of the foot-lever 7^c will elevate the plunger 7 and throw the quarter-sections 3 of the mold to the open position. Reverse movement of the foot-lever, as by means of a weight 7^e, will close the mold; or the 15 weight of the mold-sections 3 and the plunger may be depended upon to close the mold, when the pressure upon the foot-lever is removed.

The mandrel C is carried by standards 25 8 and 9 mounted on the bed-plate A, the former having a bearing 8^a in which the mandrel shaft will turn and slide freely, and the latter having a bearing, the bore of which is provided with a thread 9^a, which 30 receives a thread 10, with which the mandrel-shaft is provided at its rear end. The mandrel is provided with a tip-end 11 equipped at its base-portion with a thread 11^a of the same pitch as the thread 10. The 35 tip-portion of the mandrel is shown formed integrally with a collar 11^b, which is secured to the mandrel-shaft by means of a pin 12. It will thus be understood that the tip-portion of the mandrel is virtually integral with the mandrel shaft, and that the 40 mandrel has the rounded inner end-portion 11^c which projects some distance beyond the thread 11^a, thus forming an arbor which enters the neck-portion of the bottle beyond 45 the mouth-portion which receives the thread.

The rear end of the mandrel-shaft is equipped with a hand-wheel 13, by means of which the shaft may be turned to project or retract the mandrel. This hand-wheel is provided at its periphery with a stud 13^a which engages a stop 14 carried by the bed-plate, thus limiting the movement of the mandrel when it is projected 55 into the mold. The same stud 13^a is adapted to engage a stop 15 in the form of a bar secured to the bed-plate A, when the mandrel has turned backward a sufficient distance to disengage the thread 10 thereof 60 from the threaded bearing 9^a. The mandrel may then be withdrawn or pulled back to cause the mandrel tip 11^c to clear the mouth of the carboy. Secured to the base A is another and shorter bar 15^a which is 65 spaced a short distance from the bar 15 and

affords a slot or guide 15^b in which the stud 13^a may move when the mandrel is drawn rearwardly after it has been unscrewed from the bearing 9^a.

The collar portion 11^b of the mandrel occupies, when the mandrel is in the position shown in Fig. 1, an opening in the rear side of the mold, which is formed by complementary recesses, with which the mold-sections are provided. The mold-sections 75 are provided at their front sides with complementary recesses of suitable contour to conform to the neck-portions of the bottle, where they rest in the mold. The bottom of the cavity 6 tapers to a small discharge 80 opening 6^a, through which the hot plastic glass is forced into the mold-cavity 16.

The mechanism D for forcing the molten metal into the mold comprises a plunger 17 on the lower end of a piston rod 17^a, whose upper end is equipped with a piston 17^b; a pressure cylinder 18 adapted to receive air or other fluid under pressure, for actuating the piston 17^b in both directions; a pressure pipe 20 adapted to deliver fluid 90 under pressure to the cylinder; and a valve 21 controlling admission to and exhaust from the cylinder. The valve 21 comprises a casing 21^c and a plug 21^b therein, the plug 21^b having admission and exhaust 95 ports therethrough and being equipped with an actuating handle 21^c. The cylinder 18 is provided with ports 18^a, which serve alternately as admission and exhaust ports, for admitting pressure to either end of the 100 cylinder and exhaust from the other end. The plug valve 21^b is provided with an admission port 22, which can be placed in communication with either one of the ports 18^a, and exhaust ports 23 which are adapted 105 to discharge through a common longitudinal port 23^a, with which the plug-valve 21^b is provided.

The carriage D^a, which is movable forwardly and rearwardly, that is longitudinally with respect to the mandrel C, comprises a pair of slides 24 mounted on horizontal guide-bars 25 fixedly secured to supporting brackets 26 rigidly mounted on the bed-plate A; standards 27 fitted in the tubular sockets 24^a which are formed integrally with the tubular slides 24; and fittings 28 fixedly secured on the upper ends of the standards 27 and serving to support the cylinder 18, which is firmly connected to 115 the fittings 28, as by means of screws, or bolts, 29. It thus appears that the carriage may be shifted rearwardly to carry the cylinder 18 to the dotted position shown in Fig. 1, thus bodily shifting the mechanism D so as to uncover the mold B. The locking cams D^a comprise arms carried by split clamping-rings 19 which are secured on the uprights 27 just above the fittings 24^a. The cams D^a are adapted to make 120 125 130

sliding contact with the lock-lugs 3^c of the upper mold-sections.

The mechanism D² for shifting the carriage D¹ preferably comprises a transverse rock-shaft 30 journaled in brackets 31 secured to the rear end of the bed-plate A and equipped with a hand-lever 32 which, when the mechanism D is in operative position, inclines forwardly somewhat, as shown by the full lines in Fig. 1; a pair of short arms 33 rigidly secured to the rock-shaft; and a pair of links 34 connecting the arms 33 with the tubular slides 24. The hand-lever 32 is disposed at one side of the machine within convenient reach of an operator standing in position to actuate the foot-lever 7^c. The air-controlling lever 21^c is also located within convenient reach of the operator.

The operation may be stated briefly. Assuming the mold to have been opened to permit removal of the carboy, the operator removes the pressure upon the foot-lever 7^c, thus permitting the mold to close; he then projects the mandrel into the mold by moving it forwardly and turning it right-hand-edly, thus causing the screw 10 to engage and turn in the threaded bearing 9^a, and he then, through the medium of the hand-lever 32, shifts the pressure mechanism D forwardly from the completely retracted position to the position shown by dotted lines in Fig. 1, in which position the forward extremities of the mold-locking cams D³ engage the lugs 3^c of the upper mold-sections. Thus, the mold is locked in closed position while the cylinder 18 occupies the dotted position shown in Fig. 1, so that metal may be introduced into the mold. Before this is done, however, an assistant, standing in front of the machine, forces the neck-portion of the carboy into the mold. This is done while the carboy and particularly the neck-portion thereof is hot, so that the neck of the carboy will conform to the front orifice of the mold into which it is introduced; and inasmuch as the mold is locked at this time, it cannot be opened by the action of introducing the carboy-neck. The operator then introduces into the feed-chamber 6 of the mold the requisite quantity of molten metal (glass), and then shifts the pressure mechanism D forwardly to the full line position shown in Fig. 1. He then turns the plug-valve 21^b, through the medium of the handle 21^c, to a position to admit air pressure to the upper portion of the cylinder 18, thereby causing the piston to descend, thus forcing the molten glass through the orifice 6^a into the chamber 16 of the mold. This molds the plastic material about the mandrel and causes it to become welded or united to the neck-portion of the carboy, the mouth of the carboy being formed in this operation and provided with an internal thread. The mandrel C is then unscrewed from the bear-

ing 9^a, the screw 11^a at the operative end of the mandrel being at the same time unscrewed from the internal thread in the mouth of the carboy. When the screw 10 becomes disengaged from the threaded bearing 9^a, the mandrel is slid rearwardly longitudinally, the slot 13^a moving in the groove 15^b. Thus by this action, the mandrel is withdrawn so that the rounded tip-portion 11^c will clear the mouth of the carboy. The operator at this instant, or earlier, if desired, turns the plug 21^b so as to cause the withdrawal of the plunger 17; and at the appropriate instant, the mechanism D is shifted rearwardly to the completely retracted position by means of the lever 32, and the mold is thrown open by means of the foot-lever 7^c, thus leaving the carboy free to be lifted and withdrawn from the mold.

If desired, a suitable rest (not shown) may be arranged in front of the machine upon which the carboy may be rested by the attendant while the machine is being operated.

The improved machine is of simple construction, facile in operation, and capable of a comparatively large output of large containers, while requiring the services only of an operator and an assistant.

The foregoing detailed description has been given for clearness of understanding only, and no unnecessary limitation should be understood therefrom, but the appended claims should be construed as broadly as permissible, in view of the prior art.

What I regard as new, and desire to secure by Letters Patent, is:

1. In a machine for the purpose set forth, the combination of a base, a half-mold section mounted thereon, a pair of quarter mold sections surmounting said half mold-section and adapted to turn about horizontal pivots, said quarter-mold sections being equipped with upward extensions affording a charge-receiving cavity, a plunger adapted to force the charge from the charge-receiving cavity into the mold cavity, a mandrel having a tip-portion adapted to extend into the neck of the container and having at the base portion of the mandrel thread-forming means adapted to form internal threads in the mouth of the container, said tip-portion and thread-forming means being disposed in the mold-cavity and shiftable as a unit, and means for retracting and projecting the mandrel.

2. In a machine for the purpose set forth, the combination of a mold comprising longitudinally separable sections adapted to receive between them the neck of a container, said mold being provided at one side of the mold-cavity with a charge-receiving cavity, a mandrel adapted to form an internal thread in the mouth of the container,

said mandrel having a tip-portion adapted to extend into the neck of the container and at the base thereof thread-forming means, said tip-portion and thread-forming means 5 being disposed in the mold-cavity and adapted to be shifted as a unit, means for retracting and projecting said mandrel, and shiftably-mounted pressure mechanism provided with a plunger adapted to force the 10 molten metal from the charge-receiving cavity into the mold-cavity.

3. In a machine for the purpose set forth, the combination of a mold comprising longitudinally separable sections adapted to receive between them the neck of a container, said mold being provided at the upper side of the mold-cavity with a charge-receiving cavity, a mandrel adapted to produce an internal thread in the mouth of said container,

- 20 said mandrel having a tip-portion equipped with an external thread located in the mold-cavity and having a shaft equipped with a thread of corresponding pitch engaging a threaded stationary bearing, means for rotating said mandrel, guides extending substantially parallel with the mandrel, a forwardly and rearwardly shiftable carriage mounted on said guides and equipped above the plane of the mandrel with a pressure cylinder, a piston working in said cylinder and equipped with a plunger adapted to force the metal from the charge-receiving cavity into the mold-cavity, and means for shifting said carriage.
- 25
- 30

35 4. In a machine for the purpose set forth, the combination of a mold comprising longitudinally separable sections adapted to receive between them the neck of a container, said mold being provided at the upper side
40 of the mold-cavity with a charge-receiving cavity, a mandrel adapted to produce an internal thread in the mouth of said container, said mandrel having a tip-portion equipped with an external thread located in the mold-cavity and having a shaft equipped with a thread of corresponding pitch engaging a threaded stationary bearing, means for rotating said mandrel; guides extending substantially parallel with the mandrel, a forwardly and rearwardly shiftable carriage mounted on said guides and equipped above the plane of the mandrel with a pressure cylinder, a piston working in said cylinder and equipped with a plunger adapted to
50 force the metal from the charge-receiving cavity into the mold-cavity, a transverse rock-shaft journaled at the rear portion of the machine and equipped with arms and links joining said arms to said carriage, and
55 60 a hand-lever serving to actuate said rock-shaft.

5. In a machine of the character set forth, the combination of a bed-plate, a fixed lower mold-section mounted thereon, a pair of complementary upper mold-sections provided

with complementary upward extensions affording a charge-receiving cavity, said upper sections being mounted to swing on horizontal pivots, a plunger working through the bed-plate, links connecting the upper 70 end of the plunger with the upper mold-sections, a foot-lever accessible at one side of the machine and serving to actuate said plunger, a mandrel disposed above the bed-plate and having an operative end equipped 75 within the mold-cavity with an external thread, said mandrel being equipped back of the mold with another thread of the same pitch, a fixed bearing having an internal thread engaging said second-named thread 80 of said mandrel, means connected with the rear end of the mandrel for effecting rotation thereof, and means for forcing a charge into the mold-cavity.

6. In a machine of the character set forth, 85
the combination of a bed-plate, a fixed lower
mold-section mounted thereon, a pair of
complemental upper mold-sections provided
with complemental upward extensions af- 90
fording a charge-receiving cavity, said up-
per sections being mounted to swing on hori-
zontal pivots, a plunger working through
the bed-plate, links connecting the upper end
of the plunger with the upper mold-sections,
a foot-lever accessible at one side of the ma- 95
chine and serving to actuate said plunger, a
mandrel disposed above the bed-plate and
having an operative end equipped within
the mold-cavity with an external thread,
said mandrel being equipped back of the 100
mold with another thread of the same pitch,
a fixed bearing having an internal thread
engaging said second-named thread of said
mandrel, means connected with the rear end
of the mandrel for effecting rotation there- 105
of, bodily shiftable pressure mechanism dis-
posed above the mold and adapted to force
a charge into the mold-cavity, and means
for shifting said last-named mechanism, in-
cluding a hand-lever accessible to an op-
erator standing in position to actuate said 110
foot-lever.

7. In a machine of the character set forth, the combination of a bed-plate, a fixed lower mold-section mounted thereon and a 115 pair of complementary upper mold sections equipped at the outer sides of their lower portions with arms, pivotal supports for said arms, said upper mold-sections being provided with complementary upward extensions affording a charge-receiving cavity, 120 a plunger working through the bed-plate, links connecting the upper end of said plunger with said arms, a lever adapted to actuate said plunger, a mandrel disposed above 125 said bed-plate and having an operative end equipped within the mold-cavity with a thread, said mandrel being equipped back of the mold with another thread of the same pitch, a fixed bearing carried by the bed- 130

plate and having an internal thread engaging the second-named thread of the mandrel, means for rotating said mandrel, and means for forcing a charge into the mold-cavity.

8. In a machine of the character set forth, the combination of a bed-plate, a fixed lower mold-section mounted thereon and a pair of complemental upper mold-sections provided with complemental upward extensions affording a charge-receiving cavity, said upward extensions being mounted to swing on horizontal pivots located at opposite sides of the lower portions of the upper mold-sections, whereby the mold-sections tend to close, mechanism adapted to swing the upper mold-sections apart, said mechanism including a manually-actuated lever, a mandrel disposed above the bed-plate and having an operative end-portion equipped with a thread located in the mold-cavity and having a shaft equipped with a thread of corresponding pitch engaging a threaded stationary bearing carried by the bed-plate, means for rotating said mandrel, and means for forcing a charge from the charge-receiving cavity into the mold-cavity.

9. In a machine for the purpose set forth, the combination of a mold comprising separable longitudinal sections adapted to receive between them the neck of a container, said mold being provided at one side of the mold-cavity with a charge-receiving cavity, means for forcing the charge from said charge-receiving cavity into the mold-cavity, and a mandrel having an operative portion equipped with a thread located in the mold-cavity and a tip projecting beyond said thread into the mold-cavity and said mandrel having a shaft equipped with a thread of corresponding pitch engaging a threaded stationary bearing, and means for rotating said mandrel, the thread of said shaft being disengageable from the threaded stationary bearing to permit sliding movement to enable the tip-portion of the mandrel to be withdrawn from the container after the unscrewing operation has occurred.

10. In a machine of the character set forth, the combination of a bed-plate, a fixed lower mold-section mounted thereon and a pair of complemental upper mold-sections provided with complemental upward extensions affording a charge-receiving cavity, said upper sections being mounted to swing on horizontal pivots, mechanism for opening the upper mold-sections, including a plunger working through the bed-plate and a lever adapted to actuate said plunger, a mandrel disposed above the bed-plate and having an operative end equipped within the mold-cavity with a thread and a rounded tip beyond said thread, said mandrel having a shaft equipped with a thread of corresponding pitch engaging a threaded

stationary bearing carried by said bed-plate, means for rotating said mandrel and effecting withdrawal of the mandrel to cause the tip-portion to clear the mouth of the container, and means for forcing a charge from the charge-receiving cavity into the mold-cavity.

11. In a machine of the character set forth, the combination of a bed-plate, a fixed lower mold-section mounted thereon and a pair of complemental upper mold-sections provided with complemental upward extensions affording a charge-receiving cavity, said upper sections being mounted to swing on horizontal pivots, mechanism for opening the upper mold-sections, including a plunger working through the bed-plate and a lever adapted to actuate said plunger, a mandrel disposed above the bed-plate and having an operative end equipped within the mold-cavity with a thread and a rounded tip beyond said thread, said mandrel having a shaft equipped with a thread of corresponding pitch engaging a threaded stationary bearing carried by said bed-plate, means for rotating said mandrel and effecting withdrawal of the mandrel to cause the tip-portion to clear the mouth of the container, and bodily shiftable pressure mechanism disposed above the mold and equipped with a plunger adapted to force a charge from the charge-receiving cavity into the mold-cavity.

12. In a machine of the character set forth, the combination of a mandrel having a threaded operative end extending into the mold-cavity and a rounded tip-portion beyond the threaded portion, said mandrel having a shaft equipped with a thread, a pair of bearings for said mandrel, one of said bearings being longitudinally threaded and disengageably engaged by the thread of the shaft, means for rotating said mandrel, and stop means for limiting the rotation of the mandrel when the thread on its shaft becomes disengaged from the internally-threaded bearing, said stop means permitting the mandrel to slide longitudinally after it becomes disengaged from said threaded bearing to cause the tip-portion of the mandrel to clear the mouth of the container.

13. In a machine of the character set forth, the combination of a base, a half-mold section mounted on said base, a pair of quarter-mold sections surmounting said half-mold section and adapted to swing about horizontal pivots, said quarter-mold sections being equipped with upward extensions affording a charge-receiving cavity, a plunger adapted to force the charge from the charge-receiving cavity into the mold-cavity, a mandrel having an operative end within the mold provided with a rounded tip and an external thread at the base of said tip, said mandrel having a shaft equipped

with a thread of the same pitch, a bearing for the mandrel provided with a thread engaging the thread of said shaft, a hand-wheel connected with the rear end of said shaft, 5 and stop means for limiting the rotation of the mandrel in the unscrewing operation, said stop means permitting longitudinal shifting of the mandrel after the thread on its shaft has become disengaged from the 10 threaded bearing, thus enabling the mandrel to slide longitudinally until its tip-portion clears the mouth of the container.

14. In a machine of the character set forth, the combination of a bed-plate, a 15 lower mold-section fixedly mounted thereon and a pair of complementary upper mold-sections provided with complementary upward extensions affording a charge-receiving cavity, said upper sections being pivotally 20 mounted to permit them to be swung to open position, a mandrel disposed above the bed-plate and having an operative end equipped within the mold-cavity with a thread, said mandrel having a shaft equipped with 25 a thread of corresponding pitch engaging a threaded stationary bearing carried by said bed-plate, means for rotating said mandrel to effect withdrawal thereof, bodily shiftable pressure mechanism disposed 30 above the mold and equipped with a plunger adapted to force a charge from the charge-receiving cavity into the mold-cavity, and mold-locking means shiftable with said pressure mechanism and adapted to maintain the 35 mold in locked condition while the pressure mechanism is in a retracted position, permitting introduction of metal into the mold.

15. In a machine for the purpose set forth, the combination of a mold comprising longitudinally separable sections adapted to receive between them the neck of a container, 40 said mold being provided at one side of the mold-cavity with a charge-receiving cavity, a withdrawable mandrel having an operative end extending into the mold-cavity, shiftably mounted pressure mechanism provided with a plunger adapted to force the molten metal from the charge-receiving cavity into the mold-cavity, and mold-locking means shiftable with said pressure mechanism and adapted to maintain the mold in locked position when said pressure mechanism is in the operative position and also when said pressure mechanism is in a retracted position, 45 permitting introduction of metal into the charge-receiving cavity of the mold.

16. In a machine for the purpose set forth, the combination of a mold comprising longitudinally separable sections adapted to receive between them the neck of a container, 50 said mold being provided at the upper side of the mold cavity with a charge-receiving cavity, a withdrawable mandrel having an operative end disposed in the mold-cavity and adapted to form a thread

in the container in the molding operation, a forwardly and rearwardly shiftable carriage equipped with pressure mechanism adapted to force the metal from the charge-receiving cavity into the mold-cavity, and elongated cams carried by said carriage and adapted to maintain the mold in locked condition when the pressure mechanism is in the operative and also when it is in a retracted position, permitting introduction of a charge of metal into the charge-receiving cavity. 75

17. In a machine for the purpose set forth, the combination of a mold comprising a lower half section and a pair of complementary upper quarter sections which are pivotally mounted and provided with upward extensions, affording a charge-receiving cavity, a mandrel adapted to form an internal thread in the mouth of the container, said 80 mandrel having an operative portion equipped with an external thread located in the mold-cavity and having a shaft equipped with a thread of corresponding pitch engaging a threaded stationary bearing, means for 85 rotating said mandrel, guides extending parallel with said mandrel, a forwardly and rearwardly shiftable carriage mounted on said guides and equipped with pressure mechanism adapted to force the metal from 90 the charge-receiving cavity into the mold-cavity, and elongated mold-locking cams carried by said carriage and adapted to embrace the upward extensions of said upper mold-sections when the pressure mechanism 95 is in the operative position and also when the pressure mechanism, is in a partially retracted position, permitting introduction of the metal into the charge-receiving cavity while the mold is in locked condition. 100

18. In a machine for the purpose set forth, the combination of a mold comprising longitudinally separable sections adapted to receive between them the neck of a container, 105 said mold being provided at the upper side of the mold cavity with a charge-receiving cavity, a mandrel adapted to form an internal thread in the mouth of the container, said mandrel having a tip-portion adapted to extend into the neck of the container and having at its base-portion thread-forming means, means for projecting and retracting the mandrel, guides extending substantially parallel with the mandrel, a forwardly and rearwardly shiftable carriage mounted on 110 said guides and equipped above the plane of the mandrel with a pressure cylinder, a piston working in said cylinder and equipped with a plunger adapted to force the metal from the charge-receiving cavity into the 115 mold cavity, and means for shifting said carriage. 120

19. In a machine for the purpose set forth, the combination of a mold comprising a lower half section and a pair of complemen- 130

tal upper quarter sections which are pivotally mounted and provided with upper extensions, affording a charge-receiving cavity, a mandrel adapted to form an internal 5 thread in the mouth of the container, said mandrel having an operative portion provided externally with thread-forming means, means for projecting and retracting the mandrel, guides extending parallel with 10 said mandrel, a forwardly and rearwardly shiftable carriage mounted on said guides and equipped with pressure mechanism

adapted to force the metal from the charge-receiving cavity into the mold-cavity, and elongated mold-locking cams carried by said 15 carriage and adapted to embrace the upward extensions of said upper mold-sections when the pressure mechanism is in the operative position and also when the pressure mechanism is in a partially retracted 20 position, permitting introduction of the metal into the charge-receiving cavity while the mold is in locked condition.

HARRY M. BROWN.
